CLAIM

The ornamental design for an organizer wrap, as shown and described.

DESCRIPTION

FIG. 1 is a perspective view of an organizer wrap in an open orientation;

FIG. 2 is a front view of the organizer wrap of FIG. 1;
FIG. 3 is a back view of the organizer wrap of FIG. 1 including a hook-and-loop fastener shown in broken lines;
FIG. 4 is a right side view of the organizer wrap of FIG. 1;
FIG. 5 is a left side view of the organizer wrap of FIG. 1;
FIG. 6 is a bottom view of the organizer wrap of FIG. 1;
FIG. 7 is a top view of the organizer wrap of FIG. 1; and,
FIG. 8 is a perspective view of the organizer wrap of FIG. 1 in a wrapped orientation.

The broken lines are for purposes of illustrating environment and form no part of the claimed design.

1 Claim, 5 Drawing Sheets
